FREDERICK WINK, OF PHILADELPHIA, PENNSYLVANIA, ASSIGNOR TO
THOMAS DOLAN AND R. WILLIAMS, JR., OF SAME PLACE.

[Term of Patent 3½ years.]

To all whom it may concern:

Be it known that I, FREDERICK WINK, of the city and county of Philadelphia, State of Pennsylvania, have invented a Design for Shawl-Patterp, of which the following is a specification:

My design for a shawl-pattern, which is clearly illustrated by the figure in the accompanying drawing, consists in the peculiar arrangement and grouping of a series of wide and narrow parallel stripes, bars, or ribs of different shades or colors, some being strongly contrasted, and others shaded or blended into

each other, as shown, the complete design being illustrated in the drawing, and the remainder being merely a repetition of that which appears.

Irrespective of the colors employed, I claim—
The design for a shawl-pattern, as represented in and by the accompanying drawing.

In testimony whereof I have signed my name to this specification in the presence of two subscribing witnesses.
